DESIGN FOR AN ANIMAL TRAP OR THE LIKE

Charles E. Jones, Chicago, Ill., assignor to
Nathan R. Sklar, Chicago, Ill.

Application September 8, 1948, Serial No. 148,504

Term of patent 14 years

(Cl. D31—4)

To all whom it may concern:

Be it known that I, Charles E. Jones, a citizen of the United States, residing at Chicago, county of Cook, State of Illinois, have invented a new, original, and ornamental Design for an Animal Trap or the like, of which the following is a specification, reference being had to the accompanying drawings forming a part thereof.

In the drawings:

Fig. 1 is a side elevational view of an animal trap or the like, showing my new design.

Fig. 2 is a top plan view thereof.

Fig. 3 is a front elevational view thereof.

Fig. 4 is a rear elevational view thereof.

The dominant features of the design are shown in full lines.

I claim:

The ornamental design for an animal trap or the like, as shown and described.

CHARLES E. JONES.
